WILLIAM S. HENSON, OF NEW YORK, N. Y.

Letters Patent No. 83,060, dated October 13, 1868.

IMPROVEMENT IN ENGINE-GOVERNORS.

The Schedule referred to in these Letters Patent and making part of the same.

To all whom it may concern:

Be it known that I, WILLIAM S. HENSON, of New York city, in the county of New York, and in the State of New York, have invented certain new and useful Improvements in Governors for Steam-Engines; and do hereby declare that the following is a full, clear, and exact description thereof, reference being had to the accompanying drawings, and to the letters of reference marked thereon.

In the annexed drawings, making part of this specification, A represents a vertical spindle, which is supported by an upright sleeve or frame, B B, and which is driven by pulleys or gear-wheels in the usual manner.

The upper end of this spindle has a ball, K, formed upon it, which may be made in any ornamental manner.

F represents a collar, which surrounds the spindle A. C C represent arms, which are forked at one end, and which are provided at their other ends with the balls D D. The forked ends of these arms embrace the ball K of spindle A on opposite sides, and are connected to them by means of pivots or pins, which pass through or into the ball at an angle of about forty-five degrees, and a little to one side of the plane in which the balls D D stand, said plane being made vertically through the balls and spindle A.

The arms C C are provided, near balls D D, with the cross-heads m m, on the ends of which are formed journals.

I I represent bars, which are provided with holes near each end.

The holes in one end of these bars are fitted over the journals on the ends of cross-heads m m, while those in the other end are fitted over trunnions formed on the collar F.

When the collar F rises, the arms C C extend in

the usual manner. The collar and the bars I act as guides and supports for the arms C and their balls.

In describing the operation of this governor, suppose it to be revolving, in the direction indicated by the arrows, at a suitable velocity to cause the balls D D to fly upward by the centrifugal force further from each other than is shown in the drawings at Figure 1, to about the position indicated in red lines; then, when the revolving motion of the spindle is retarded, the momentum of the balls will instantly cause them to advance faster than the spindle, with an angular descending motion, which is communicated to the engine through the grooved pulley F, and the other usual connections; but when the engine creates a higher velocity in the revolving spindle, the inertia of the balls D D will cause them to move instantly with a backward, upward, and outward motion relative to the spindle, which is also communicated through the connecting-parts to the engine.

This governor acts more quickly and more sensitively than those now in use.

Having thus fully described my invention,

What I claim as new, and desire to secure by Letters Patent, is—

The revolving spindle A, collar F, and ball K, connected to which are the forked arms C C, cross-heads M M, balls D D, and pivoted bars I I, the several parts being constructed, arranged, and operating substantially in the manner as specified.

In testimony that I claim the foregoing, I have hereunto set my hand and seal, this 29th day of February, 1868.

WM. S. HENSON. [L. s.]
